UNITED STATES PATENT OFFICE.

JOHN V. SYBRANDT, OF SPRINGDALE, COLORADO.

UMBRELLA.

No. 802,719.

Specification of Letters Patent.

Patented Oct. 24, 1905.

Application filed November 16, 1904. Serial No. 232,967.

To all whom it may concern:

Be it known that I, JOHN V. SYBRANDT, a citizen of the United States, and a resident of Springdale, in the county of Boulder and State of Colorado, have invented a new and Improved Umbrella, of which the following is a full, clear, and exact description.

My invention relates to umbrellas and similar articles, and is capable of application to canopies, tents, and the like.

The chief object of the invention is to provide means whereby an article of the class mentioned can be made of any desired form without interfering with its capability of being folded.

Other objects are to provide for mounting such an article at any desired angle and to apply curtains thereto.

Further objects of the invention will appear in the course of the subjoined description.

Reference is to be had to the accompanying drawings, forming a part of this specification, in which similar characters of reference indicate corresponding parts in all the figures.

Figure 1 is a side elevation of a carriage, showing one form of my invention applied thereto. Fig. 2 is a bottom plan view of the umbrella shown in Fig. 1. Fig. 3 is a side elevation, on an enlarged scale, of a portion of

the framework of an umbrella constructed on the same principle. Fig. 4 is a longitudinal sectional view, on an enlarged scale, of the same. Fig. 5 is a sectional view on the line 5 5 of Fig. 4 on an enlarged scale. Fig. 6 is

a rear elevation of a vehicle, showing the umbrella-stick and means for securing it in different positions. Fig. 7 is a sectional view, on an enlarged scale, showing the adjusting means illustrated in Fig. 6; and Fig. 8 is a

fragmentary view showing a detail.

I accomplish the first object mentioned above by making the ribs of different lengths, according to the desired shape of the canopy.

It is to be understood that when the word "canopy" is used in this specification it signifies other articles of a similar nature—as, for example, an umbrella or a tent—and that the invention is capable of application to these other devices.

Fig. 1 represents a vehicle *a*. An umbrella *b* is supported therein by a stick *c*. The umbrella, as shown in Fig. 2, is rectangular in form and is provided with three series of ribs *d*, *d'*, and *d''* of different lengths. These ribs are all pivotally attached to the crown *e*, which is secured to the stick in the usual or

any desired manner. By providing ribs of different lengths it will be understood that umbrellas or other articles of the classes mentioned above can be made of any desired shape. They can project out a distance on one side, so as to cover several seats in the vehicle, or they can be made elliptical, and when used for tents it will be obvious that the shapes which they may assume will be unlimited. Pivots connected with the ribs are three series of spreaders *f*, *f'*, *f''*. Each set of spreaders is connected with an independent slide, the three slides thus provided being designated *g*, *g'*, and *g''*, respectively, as shown in Fig. 3. The ribs of the longest set *d* are connected, by means of their respective spreaders, with the lowest one of these slides *g*. The shorter sets of ribs are connected, by means of their respective spreaders, with the slides *g'* and *g''*, which are located above the first-mentioned slide *g*. The slides *g'* and *g''* are freely movable upon the stick. The slide *g*, however, is provided with a perforation *g*⁴ and with a catch *g*⁴ of the ordinary or any desired kind. The stick *c* is also provided with a perforation or indentation *c'*, with which the end of the catch engages. It will be readily understood that when it is desired to raise the umbrella the slide *g* is forced upwardly until it picks up the slides *g'* and *g''* and carries them with it to their uppermost point, at which time the end of the catch *g*⁴ is opposite the indentation *c'* and the catch is then forced into the indentation by its spring *g*⁵. To lower the umbrella, the operation will be reversed in an obvious manner.

In order that the umbrella may be placed at any desired height with respect to the stick, the latter is made in two parts. The upper part *c*, which has been referred to above, is preferably in the form of a tube, and the lower part *h* may be tubular or solid, but is small enough to enter the tube *c*. This forms a telescopic joint, and rotation of the umbrella is prevented by means of a groove *h*¹ in the member *h* and an internal projection *c*² on the tubular portion of the stick. In order to secure the part *c* with respect to the part *h* when they are once adjusted to the proper position, a nut *i* is provided upon the lower end of the tube *c*. This nut is threaded at *i'* for only a portion of its length, so that it can be screwed up and down upon the tube. A key *j* is mounted between the nut and the tube and is provided with a roughened or serrated face *j'*, passing through an opening *c*³.

in the tube. It will be readily observed that upon tightening the nut by screwing it upwardly upon the tube it will bind the inclined rear surface of this key so as to force its 5 roughened face j' through the opening c' and into contact with the part h of the stick. This nut can be so tightened as to cause this contact to be maintained under great pressure and to prevent the sliding of one portion of 10 the stick upon the other.

In order to adjust the position of the stick with respect to the vehicle, a rod k , as shown in Figs. 6 and 7, is provided at any convenient point—as, for example, upon the back of the 15 seat. A bracket l is preferably placed upon this rod and secured to the rod by means of a thumb-screw l' . The stick c passes through a perforation l'' in the bracket. On the bottom of the stick is a projection h^2 , which 20 enters an opening in the floor of the vehicle or in any other support, providing a pivotal connection between the stick and the support. In order that the stick may swing upon this 25 pivot, the rod k is preferably made in the form of an arc of a circle, having this pivot as its center. On the inside of the umbrella a chain m is provided and is connected with the several ribs just within the outer edge of the 30 cover. This chain assists in holding the ribs and preventing them from being torn from each other in a high wind, and by being located at this point the fringe can be hung thereon to produce a neater appearance, and the fringe will be protected from the drippings 35 from the edge of the umbrella.

Another important feature of my invention consists in a curtain n , which is removably connected with the umbrella at any desired point. For example, it may be applied to 40 the rear end or to a half of one side, as shown in Fig. 1. This curtain is made removable and is connected to the umbrella by means of hooks n' . These hooks can conveniently be attached to the chain at any desired point and 45 without the necessity of hunting for an eye.

While I have illustrated and described one embodiment of my invention, it is to be understood that it is not strictly limited thereto, but that it may be constructed in many other 50 forms and that many modifications may be made in the form shown. Also, it may be applied to all kinds of canopies and tents and other articles of a similar nature. It will be observed that when this principle is employed 55 articles of this character can be made of any desired form without interfering with their capability of being folded into a compact position on the stick, also that an improved stick capable of providing any desired 60 adjustment in the height of the top has been disclosed, as well as an improved manner of mounting the stick upon a vehicle or any other desired support, and it will also be understood that more or less than three slides 65 may be employed, if found desirable.

Having thus described my invention, I claim as new and desire to secure by Letters Patent—

1. An umbrella, comprising a pair of telescoping elements longitudinally adjustable with respect to each other, the outer one having a perforation, a longitudinal tongue-and-groove connection between said elements, and a key secured to the outer element and provided with a roughened face adapted to project through the perforation of the outer element into engagement with the inner one. 75

2. An umbrella comprising a pair of telescoping elements longitudinally adjustable with respect to each other, the outer one having a perforation, a longitudinal tongue-and-groove connection between said elements, a key secured to the outer element and provided with a roughened face adapted to project through the perforation of the outer element into engagement with the inner one, and 80 means for securing said key to the outer element. 85

3. An umbrella comprising a pair of elements longitudinally adjustable with respect to each other, the outer one having a perforation, a nut having a plane internal surface and a screw-threaded internal surface having screw-threaded engagement with the outer of said elements, and a key having an inclined rear face adapted to be secured between the 95 plane surface of said nut and the outer element and provided with means for engaging with the inner element through said perforation. 90

4. An umbrella comprising a pair of telescoping elements longitudinally adjustable with respect to each other, the outer one having a perforation, a longitudinal tongue-and-groove connection between said elements, a nut having a plane internal surface and a 100 screw-threaded internal surface, and having screw-threaded engagement with the outer of said elements, and a key having an inclined rear face adapted to be secured between said nut and the outer element and provided with 105 a roughened face adapted to project through the perforation of the outer element into engagement with the inner one. 110

5. A rectangular foldable canopy or umbrella provided with a chain secured to the 115 ribs near their outer ends, in combination with a curtain provided with hooks and removably secured to said chain.

6. An umbrella, comprising a pair of telescoping elements longitudinally adjustable 120 with respect to each other, the outer one having a perforation, a longitudinal tongue-and-groove connection between said elements, a nut having a plane internal surface and a screw-threaded internal surface and having 125 screw-threaded engagement with the outer of said elements, a key having an inclined rear face adapted to be secured between said nut and the outer element and provided with a roughened face adapted to project through 130

the perforation of the outer element into engagement with the inner one, a series of slides mounted upon one of said elements, and a plurality of series of ribs of different lengths, 5 the ribs of each length being connected with one of said slides.

In testimony whereof I have signed my name

to this specification in the presence of two subscribing witnesses.

JOHN V. SYBRANDT.
